UNITED STATES PATENT OFFICE.

WILLIAM H. PAULDING, OF PEEKSKILL, NEW YORK.

CURTAIN-FIXTURE.

SPECIFICATION forming part of Letters Patent No. 269,703, dated December 26, 1882.

Application filed March 28, 1882. (No model.)

To all whom it may concern:

Be it known that I, WILLIAM H. PAULDING, of Peekskill, in the county of Westchester and State of New York, have invented a new and useful Improvement in Fixtures for Shades or Curtains for Windows, Doors, or other apertures where a shade or curtain may be required, of which the following is a specification.

10 This improvement will prove particularly useful for the windows of railroad-cars.

In the accompanying drawings, Figure 1 is a view of my device with the curtain-slat engaging therewith, and Fig. 2 is a side view of 15 the same.

In the ordinary window-shade running upon a spring-roller it is liable to run unevenly, and if the window is open to be blown out or in.

20 My improvement and invention consists in fastening to the bottom of the shade or curtain a stick or slat of wood or metal, or combination of the two, extending beyond the fabric at either end.

25 On the sides of the window, door, or other aperture I place ratchets or catches of any suitable size, shape, or arrangement of wood, metal, or other suitable material. The ratchets or catches are placed opposite to each other on 30 the sides of the frame next the opening, and the stick or slat at the bottom of the shade or curtain is constructed of sufficient length to reach and engage in these catches or ratchets. This stick or slat is preferably made flat and beveling, with the thinner edge upward, so as 35 to readily hold in the catches or ratchets with a stop placed on the sides of the frame a convenient distance from the ratchets, so that the stick and shade may not be blown out from 40 the opening; or a groove may be sunk in either side of the frame of the aperture and the ratchets placed on one side of the groove, the other side of the groove operating as the stop, a suitable slot being cut out either top or bottom to

admit the overreaching ends of the curtain stick 45 or slat. By this method the constant tension of the spring-roller against the shade stick or slat, the ends of which are engaged in the ratchets or catches, keeps the shade always in place and flat, keeps it from flapping in the 50 wind, and enables it to be rolled and unrolled evenly.

In the accompanying drawings, intended to form part of this specification, A A' are the sides of a window or other frame.

b is an ordinary spring-roller with shade partially rolled on it.

C is the shade or curtain.

D is the slat, attached at the bottom of the shade or curtain, extending beyond the curtain and the ends engaged in the ratchets.

E is a ratchet attached to the frame A', a similar ratchet being attached to the corresponding frame, A, in a similar manner, the stick D extending over and engaging in them 65 on both sides.

F is a stop placed at a convenient distance to prevent the stick D from being blown out of the catches.

Having thus described my invention, I claim 70 and desire to secure by Letters Patent of the United States—

1. The combination of the stick D, with the ratchets or catches placed on either side of the frame, substantially as described.

2. The ratchets or catches E, constructed and shaped as shown, and attached to the frame of a window or other similar aperture to hold in any required place a shade or curtain, substantially as described.

3. The combination of the spring-roller b, the shade C, the stick D, the ratchets or catches E, and the stop F, substantially as described.

WM. H. PAULDING.
